UNITED STATES PATENT OFFICE.

JOHN LODEWICK, OF TROY, NEW YORK.

DESIGN FOR SLEIGHS.

Specification forming part of Design No. 7,151, dated February 3, 1874; application filed January 9, 1874.
[Term of Patent 7 years.]

To all whom it may concern:

Be it known that I, JOHN LODEWICK, of Troy, county of Rensselaer, State of New York, have invented a Design for Sleigh, of which the following is a specification:

The nature of my design is fully represented in the accompanying photographic illustration, to which reference is made.

A represents the body of that class of sleighs known to the trade as the swell-side barouche-sleigh, having a front passenger-seat, B, rear passenger-seat C, and a driver's-seat, F. Instead of forming the front portion of the body of the sleigh with a curved sweep, unbroken from the front of the seat F to its juncture with the goose-neck a , as heretofore, I form the said line with a flattened sweep, a' , commencing at the driver's seat and terminating at a^2 , with the front panel b at about the bottom of the platform on which the driver stands; and instead of forming the back panel of the body with a continuous sweep-line from x to z , as heretofore has been the custom, I continue the said sweep-line from x , at the rear of the back knee, to y , which is at a point a little above a line with the back-seat bottom, and from the said point y I form the flat panel e , extending from y to z , so that the rear panel, which heretofore was made in a continuous convex form from y to z , will be made to comprise two panels, the lower one of convex form and the other of flat form, which may or may not be separated by a molding or bead, as fancy might suggest. Instead of making the upper line of the belt and crest panel with a succession of sweep-lines from the rear of the driver's seat to its extreme point at the back of the sleigh, I form the first line d from the rear of the driver's seat to the front of passenger seat B, thence the straight lines s s^1 s^2 , the lines s and s^2 made oblique, as shown, instead of the usual concave sweep-line. I then form the upper line of the arm of the back passenger-seat C with

a slight curve, n , commencing at the oblique straight line s^2 and running back to the rear of the sleigh. The sides of the front passenger-seat is formed by a rail, m , and at the rear termination of the said rail is placed the back o of the front passenger-seat B. The lower line of the main body-panel is made with the usual sweep-line heretofore used, and terminates with the sweep-line a^1 at a^2 . The several panels may be variously painted, and ornamented with stripings or other ornaments.

By this design the body of the sleigh, in its construction, is not in the least weakened, and the graceful lower curve of the lower panel is preserved, while all that part above the said lower panel is greatly changed in appearance, and gives to the beholder an appearance of ease and graceful form, with less curved lines than heretofore has been associated with this class of sleighs, while the back of the sleigh is made to appear to be lighter, and present a break to its surface, giving, in effect, two distinct and diverse styles of panels not before used in the backs of this style of sleighs.

What I claim, and desire to secure by Letters Patent, for design in sleighs, is—

1. The design formed by the sweep-line a' , commencing at the driver's seat F, in front, and terminating at a^2 , forming an angle with the line a of the goose-neck, substantially as described and shown.

2. The design formed by the upper line of the body, formed of the sweep-lines a^1 and d , straight lines s s^1 s^2 , and line n , substantially as described and shown.

3. The design formed by the flat panel e , commencing at y and running up to the top, in combination with the convex panel below, commencing at y and running to x , substantially as described and set forth.

JOHN LODEWICK.
